UNITED STATES PATENT OFFICE.

BENJAMIN FORD, OF MIDDLEBOROUGH-ON-TEES, ENGLAND.

IMPROVEMENT IN HOT-BLAST STOVES.

Specification forming part of Letters Patent No. 124,803, dated March 19, 1872.

To all whom it may concern:

Be it known that I, BENJAMIN FORD, of Middleborough-on-Tees, England, have invented a new and useful Improvement in Hot-Blast Stoves; and I do hereby declare that the following is a full, clear, and exact description of the same, reference being had to the accompanying drawing forming part of this specification, and in which—

Figure 1 represents a vertical longitudinal section of a hot-blast stove constructed in accordance with my invention, and as designed to be heated by the waste gases of a furnace; Fig. 2, a vertical transverse section in part thereof at the line *x x* in Figs. 1 and 3; Fig. 3, a horizontal section of the same at the line *y y* in Fig. 1; and Fig. 4, a vertical longitudinal section in part, and upon a larger scale, showing the base portion of two of the stand-pipes in part, as fitted to their places in a detached or separate base box. Fig. 5 is a vertical longitudinal section of a like construction of hot-blast stoves as heated by the products of combustion from a fire-place or series of fire-places at its one end.

Similar letters of reference indicate corresponding parts throughout the several figures of the drawing.

My invention consists in a hot-blast stove made up of a series of flat stand-pipes of novel construction, and arranged so as to form a wall running in direction of the flow of the heated gases within a chamber or casing through which said gases pass on both sides of the wall of pipes, the stove being composed of a series of such walls and inclosing chambers, forming stove sections, and arranged side by side, and the pipes being fitted into or resting on separate boxes at their base, and the roof of the chamber being fitted with separate boxes over the stand-pipes. The gas, entering at the hot end, flows horizontally along the faces of the pipes into vertical flues at the cold end, the gas traveling against the blast, which ascends and descends the pipes.

By my improved construction there is an increased efficiency in heating the blast; the stove is less liable to get out of repair consequent upon expansion and contraction, or from other causes; the facility for repairs and cleaning is enlarged; and the cost of first erection

is less, and the working economy greater, than that of other hot-blast stoves.

Referring, in the first instance, to Figs. 1, 2, 3, and 4 of the drawing, A A represent the chambers of two adjacent sections, of which there may be any number, arranged side by side, according to the required capacity of the stove. Said chambers, which are built of brick, are of similar construction and similarly fitted or provided as regards interior and other appliances, so that a description of one stove section answers for all. B B are the stand-pipes erected within each chamber A, one in rear of the other, so as to form a wall of pipes exposed to the full action of the gases on and around them, and being free at their upper ends; also of a flat construction, so as to present their broad sides to the direct action of the gases or flame and heated currents in directions parallel or thereabout with the course of the gases through the chamber, and so that said gases cover their whole surface equally on both sides. Thus constructed and arranged the whole area of the pipes is made an effective heating surface. Said pipes, too, are closely incased by the fire-brick walls of the chamber in which they stand, thereby keeping the flame and heated currents close to the surface of the pipes. These brick walls soon become incandescent, and act as effective radiators and reflectors of the heat to the parallel broad surfaces of the pipes. The hot gases are admitted from above through a valve, C, into a vertical combustion-chamber, D, at the one end of the structure, and pass through vertical elongated side openings b b into the chamber A, for travel therethrough and among the pipes B B, finally passing out through similar openings c c to the chimney E, or down draught, if preferred. The cold blast to be heated is admitted by a pipe, F, at the upper portion of the opposite end of the structure, and caused to descend within the chamber A and to enter the first of the boxes G G, on which the pipes B B stand. Said pipes have an arched division, d, at their base, terminating in or forming part of a vertical partition, e, which stops short of the top of the pipe, and on either side of this partition are other parallel diaphragms or partitions f f arranged in close proximity to the top of the pipe, but stopping

short of its base. Each pipe B stands upon and communicates with two adjacent base-boxes, and has its divided foot incased by rings *g g*, and secured by luting. The cold blast, entering the first base-box G of the series, passes up the two nearest vertical flues formed by the diaphragms in the pipe, and down the two more distant flues thereof, and from thence into the next box B, and up and down in a similar manner the next pipe in the series, and so on in succession throughout the whole series of base-boxes and pipes, and finally passing upward and out by a pipe, H, at the hottest end of the chamber. The dotted arrows in the drawing indicate the course of the heated gases, and the arrows in full lines the course of the blast.

From this description it will be seen that the greater part of the connections, which in other stoves are on the outside, in this arrangement are kept inside, and instead of operating to cool the blast act as heating surfaces. It is preferred to construct the stove in at least eight sections, and to divide the necessary blast for a single furnace up among them, admitting the same by pipes of large sectional area compared with the quantity of blast passing through them, whereby the blast passes more slowly and remains longer under the action of the heat. The friction of the blast, also, in passing through the stove, is reduced to a minimum, and little or no difference of pressure exists at the tuyere.

The roof of the stove is fitted with a series of separate boxes, I I, containing brick filling, and arranged over the stand-pipes B B to allow of the lifting out of any one of said pipes and inserting another when necessary, by merely cutting the ring that makes the joint of the box and removing its brick filling. By this provision the pipes, or any interior portion of the stove, can be taken out and replaced without destroying the main brick work, and in an incredibly short space of time, and with but little labor; also, any one section be thus opened for repair without interfering with the other sections of the stove or materially impairing the action of the latter. A hot-blast stove constructed as described, however, is but little liable to get out of repair, inasmuch as the pipes B B are equally heated, consequently subject to equal expansion and contraction, and free from straining and bending, being free at their upper ends, thus preserving the integrity of the stove and preventing break or loss of blast at the joints. Said pipes, too, are

constructed without a bend at their tops, consequently they are less liable to accident, and having a large sectional area and being braced by three or more diaphragms each, an efficient heating surface is obtained, combined with great strength of pipe. Furthermore, the number of pipes is diminished.

The same advantages which accrue to the repairing of the stove when constructed as described apply with equal force as regards facility to the cleaning of it, nor need the stove be stopped or cooled down for either purpose; also, room is afforded for workmen on the inside of a section. The stoppage of a stove for either of such purposes is a great drawback in the manufacture of iron by hot-blast, and is liable to damage the stove.

Lastly, the cost of erection and the working expense of a stove constructed as described is reduced, the quantity of cast-iron, which is the most expensive item, being very small; and yet a higher temperature may be attained with perfect safety than is practicable with metal stoves generally. The economy of fuel is greater, because the products of combustion must pass along the whole surface of the pipes, and the heat be taken up by the blast before said products reach the chimney.

Fig. 5 of the drawing shows a similar construction of stove heated by a fire-place or series of fire-places, J, arranged below.

What is here claimed, and desired to be secure by Letters Patent, is—

1. The combination of the flat stand-pipes B, left free at their upper ends, with the chamber or casing A, when arranged to form a wall running in direction of the length of said chamber, substantially as specified.

2. The combination of the separate base-boxes G with the stand-pipes B, the inlet blast-pipe F, and outlet blast-pipe H, the chamber A, and its inlets *b* and outlets *c*, essentially as described.

3. The combination of the upper boxes I with the separate stand-pipes B and their base-boxes G, substantially as specified.

4. The independent stand-pipes B, of a flattened construction, and provided with three or more vertical diaphragms, *e* and *f*, in combination with the base-boxes F, essentially as herein set forth.

BENJAMIN FORD.
